US0D1065209S

(12) **United States Design Patent** (10) **Patent No.:** **US D1,065,209 S**
(45) **Date of Patent:** **** Mar. 4, 2025**

(54) **LAPTOP COOLING PAD**

(71) Applicant: **Shenzhen Xinhemei E-commerce Co., Ltd.**, Guangdong (CN)

(72) Inventor: **Gang Xie**, Guangdong (CN)

(**) Term: **15 Years**

(21) Appl. No.: **29/898,375**

(22) Filed: **Jul. 26, 2023**

(51) **LOC (15) Cl.** **14-02**

(52) **U.S. Cl.**

USPC **D14/447**

(58) **Field of Classification Search**

USPC D14/447, 251, 252, 253, 440, 451, 452, D14/448, 449, 450, 217, 356, 432, 434, D14/439; D3/215, 220, 250, 293, 328; D6/323, 682.3, 684, 547, 706, 512, 513, D6/574; D8/367

CLAIM

The ornamental design for a laptop cooling pad, as shown and described.

DESCRIPTION

FIG. 1 is a perspective view of the laptop cooling pad showing my new design;

FIG. 2 is another perspective view of the laptop cooling pad showing my new design;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 a partial enlarged view of portion 9 in FIG. 2;

FIG. 10 a partial enlarged view of portion 10 in FIG. 3; and, FIG. 11 is another perspective view of the laptop cooling pad showing my new design.

The broken lines in the figures illustrate portions that form no part of the claimed design.

1 Claim, 11 Drawing Sheets
